CLAIM

The ornamental design for a vent, as shown and described.

DESCRIPTION

FIG. 1, is a front perspective view of a first embodiment of a vent.

FIG. 2 is a front view of the first embodiment of the vent shown in FIG. 1.

FIG. 3 is a back view of the first embodiment of the vent shown in FIG. 1.

FIG. 4 is a right side view of the first embodiment of the vent shown in FIG. 1.

FIG. 5 is a left side view of the first embodiment of the vent shown in FIG. 1.

FIG. 6 is a top view of the first embodiment of the vent shown in FIG. 1.

FIG. 7 is a bottom view of the first embodiment of the vent shown in FIG. 1.

FIG. 8 is a back perspective exploded view of the first embodiment of the vent shown in FIG. 1.

FIG. 9 is a front perspective exploded view of the first embodiment of the vent shown in FIG. 1.

FIG. 10 is a front perspective view of a second embodiment of a vent.

FIG. 11 is a front view of the second embodiment of the vent shown in FIG. 10.

FIG. 12 is a back view of the second embodiment of the vent shown in FIG. 10.

FIG. 13 is a right side view of the second embodiment of the vent shown in FIG. 10.

FIG. 14 is a left side view of the second embodiment of the vent shown in FIG. 10.

FIG. 15 is a top view of the second embodiment of the vent shown in FIG. 10.

FIG. 16 is a bottom view of the second embodiment of the vent shown in FIG. 10.

FIG. 17 is a back perspective exploded view of the second embodiment of the vent shown in FIG. 10.

FIG. 18 is a front perspective exploded view of the second embodiment of the vent shown in FIG. 10.

FIG. 19 is a front perspective view of a third embodiment of a vent.

FIG. 20 is a front view of the third embodiment of the vent shown in FIG. 19.

FIG. 21 is a back view of the third embodiment of the vent shown in FIG. 19.

(Continued)

FIG. 22 is a right side view of the third embodiment of the vent shown in FIG. 19.

FIG. 23 is a left side view of the third embodiment of the vent shown in FIG. 19.

FIG. 24 is a top view of the third embodiment of the vent shown in FIG. 19.

FIG. 25 is a bottom view of the third embodiment of the vent shown in FIG. 19.

FIG. 26 is a back perspective exploded view of the third embodiment of the vent shown in FIG. 19.

FIG. 27 is a front perspective exploded view of the third embodiment of the vent shown in FIG. 19.

The broken line showing of a vent is include for the purpose of illustrating portions of the article and forms no part of the claimed design.
